BASE OF A FLOOR MACHINE

Robert C. Albers, Lakewood, Ohio, and John W. Albers, Ballwin, Mo., assignors to Hadco Corporation, Cleveland, Ohio

Filed Oct. 21, 1969, Ser. No. 19,652

Term of patent 14 years

Int. Cl. D15—05

U.S. Cl. D37—1

FIG. 1 is a perspective view of the base of a floor machine embodying our new design as seen from the left front of the machine;

FIG. 2 is a top plan view thereof; and

FIG. 3 is a side elevation view as seen from the right side of FIG. 2.

The side not shown is substantially the same as the one shown in FIG. 3.

In each of the views the base of the floor machine is fully shown and the handle and wheel braces are only fragmentarily shown in dotted lines for illustrative purposes only.

We claim:

The ornamental design for the base of a floor machine, substantially as shown and described.
